CAPSULE-FILLING DEVICE WITH CAPSULE HOPPER FEED

Gerald B. Lawrence, New York, and Jules A. Huberman, Brooklyn, N. Y.; said Lawrence as signor to said Huberman

Application January 3, 1951, Serial No. 204,108

10 Claims. (Cl. 226—41)

1

The present invention relates to a device for automatically filling capsules for medicinal and allied purposes.

An object of this invention is to provide an apparatus adapted to receive a load or clip of closed but empty capsules and having means for automatically uncapping these capsules, loading them with a powder from a suitable reservoir, recapping the loaded capsules and ejecting them ready for sale or storage.

Another object of the invention is to provide an apparatus of the character set forth above wherein contamination of the powder is positively prevented by virtue of the fact that the powder, before being loaded into the capsule, comes into contact only with a few selected parts which in turn are of non-oxidizable material, such as aluminum or stainless steel, and are readily removable for cleaning and sterilization.

A further object of the invention is to provide an apparatus as specified which will accommodate a variety of sizes of capsules without requiring more than the exchange of a few readily accessible parts.

Still another object of the instant invention is to provide an apparatus in accordance with the foregoing which will rapidly and dependably process, one after the other, a large number of capsules placed in its hopper and which will perform the necessary operations, including starting and stopping, without requiring the attention of an operator.

Yet a further object of this invention is to provide mechanism of relatively simple and inexpensive construction for the purpose of performing the various functions of the apparatus outlined above.

The invention will be described with reference to the accompanying drawing which shows a now preferred embodiment. In the drawing:

Fig. 1 is a top plan view of an apparatus according to the invention;

Fig. 2 is a sectional elevation taken substantially on the line 2—2 of Fig. 1;

Fig. 3 is a horizontal section taken substantially on the line 3—3 of Fig. 2;

Fig. 4 is a fragmentary sectional elevation taken substantially on the line 4—4 of Fig. 3;

Fig. 5 is a fragmentary sectional plan view on the line 5—5 of Fig. 2;

Fig. 6 is a sectional elevation taken substantially on the line 6—6 of Fig. 2; and

Fig. 7 shows the overall circuit diagram of the apparatus illustrated in the preceding views.

The apparatus shown in the drawing comprises

2

a frame or casing which consists of a top platform 11, a bottom platform 12 and side walls 13, 14. Top platform 11 is provided with a circular cutout 15 (Fig. 2) and with a second, cartridge-shaped cutout 16 below which there is formed a dependent socket 17. The socket 17 may be of rectangular shape externally, as shown, its interior being of the same horizontal cross section as and in registry with the cutout 16; the socket walls are traversed by a bottom opening 18, a side hole 19 provided at the flat right-hand end of the cartridge-shaped socket chamber, and a discharge port 20 provided at the round left-hand end thereof. Port 20 opens into a downwardly curved discharge tube 21 secured by means of a flange 22 to the socket 17.

The socket 17 is adapted to receive a hopper or magazine 23 which is introduced into it from above through the cutout 16 and which contains a supply of empty capsules 24 each closed by a cap 25. The capsules are stacked in horizontal position within the oblong hopper chamber, with the caps 25 thereof facing the flat right-hand end of the hopper. At the lower extremity of the hopper 23 there is provided a small hole 26 in alignment with the hole 19 and a large hole 27 in alignment with the port 20. A weight 28, shaped to fit slidingly within the hopper chamber, bears upon the topmost capsule 24 while the cap of the lowermost capsule depresses a switch arm 29 extending through the bottom opening 18. Arm 29 forms part of a micro-switch 30 which controls the starting and the stopping of the apparatus in a manner subsequently described in connection with Fig. 7. The weight 28 is provided at its underside with a recess 31 designed to receive the switch arm 29 when the weight reaches the bottom of the hopper 23, this situation occurring after the last capsule 24 has been ejected therefrom by the action of a solenoid 32 whose plunger 33 is positioned to penetrate the side holes 19, 26 for the purpose of ejecting each capsule through the ports 20, 27 and the tube 21. The micro-switch 30 has a low enough operating torque to respond to the pressure exerted by one or more capsules 24 as well as the weight 28, the latter being, of course, sufficiently light to prevent crushing or serious deformation of the gelatin shells forming these capsules.

Swingable through a horizontal angle of ninety degrees is a J-shaped control arm 34 the two branches of which are journaled on rod 35 supported in the platforms 11 and 12, the lower, shorter branch of the J resting on a shoulder

36 of the rod. Between these two branches there are positioned three vertically oriented electro-magnets 37, 38 and 39, spaced approximately forty-five degrees apart on an arcuate support 40 which carries pins 41, 42 to limit the swing of the arm 34. The right-hand extremity of this arm (as viewed, for example, in Figs. 2 and 3) acts as an armature for these magnets and, by virtue of its bent shape, forms an almost completely closed magnetic circuit with the core of 10 whichever magnet it is aligned with; selective energization of the magnets 37, 38 and 39 will, therefore, have the effect of pulling the arm 34 into a respective one of three operating positions spaced forty-five degrees apart, as best 15 seen in Fig. 3 where the first two of these positions (associated with magnets 37 and 38) have been indicated in dot-dash lines and the third position (associated with magnet 39) has been shown in full.

It will be noted in this connection that the cores of the outermost magnets 37 and 39 are positioned in slightly overlapping relationship with the pins 41 and 42, respectively, so that energization of either of these magnets will tend to displace the arm 34 beyond the limits of its operating arc. This arrangement will have the effect of positively indexing the control arm in either its first or its third position as defined by the contact between the arm and the respective pin 41, 42. Means for positively indexing the arm in its second, or intermediate, position will be described later on.

The arm 34 carries a horizontal plate 43 provided with a funnel-shaped aperture 44 below which there is positioned the plunger 45 of a solenoid 46 mounted on the underside of the plate. In the first operating position of arm 34 and plate 43 (Fig. 6) the aperture 44 is located directly under the lower end of the discharge tube 21 so as to receive an empty capsule 24 ejected through that tube, the bottom of the capsule coming to rest on the cup-shaped top of the plunger 45 just below the plate 43. Aperture 44 is flanked by the movable jaw 47 and the horizontally fixed jaw 48 of a first gripper which is controlled by an electromagnet 49, the latter being lodged in a recess 50 of the plate 43. Two pins 51 secure the stationary jaw 48 to the plate 43 while a third pin 52, also rising from this plate, serves as a pivot for the movable jaw 47. The free extremity of the jaw 47 forms an armature 53 for the magnet 49 and plays in a cutaway portion of the bottom of recess 50. Normally, i. e. with the magnet 49 de-energized, the movable jaw 47 is held away from its mate 48 by a spring 54. The stationary jaw 48 forms an obtuse angle around the aperture 44 and is lined with a pad 55 of sponge rubber or the like, designed to afford firm yet resilient contact with a capsule 24 engaged by the gripper. As best seen in Fig. 6, the height of the jaws 47, 48 is such that the gripper will engage only the body of the capsule but not the cap 25 thereof. Both jaws are slideable on their respective pins 51, 52 so that they may rise with respect to the plate 43, against the action of respective springs 56, 57, when the solenoid 46 operates to lift the capsule 24 from its seat under circumstances hereinafter set forth.

In its second operating position (Fig. 4) the plate 43 is aligned with a similar plate 58 tiltably mounted above the former by means of a bracket 59 depending from the platform 11. The underside of plate 58 is provided with a cup-shaped recess 60 adapted to receive the cap 25 of a capsule 75

24 held in the first gripper 47, 48. Recess 60 is flanked by the movable jaw 61 and the stationary jaw 62 of a second gripper which is in all respects similar to the first gripper except that its jaws are not slideable relative to the plate 58. The pivot for the jaw 61 is shown at 63. This jaw is controlled by an electromagnet 64, lodged in a recess of the plate 58, and by a restoring spring (not shown) similar to spring 54 of the lower pair.

Normally the plate 58 is tilted upwardly, as shown in Fig. 2 and in full lines in Fig. 4, so as to clear the plate 43 and the gripper 47, 48 carried thereon. It then abuts the end of a horizontal extension 65 of the bracket 59 to which is secured a spring 66 holding the plate in its tilted position. Adapted to swing the plate 58 downwardly about its pivots 67 (only one shown) is an electromagnet 68 supported on the bracket 59 and co-operating with an armature 69 provided on the rear end 20 of the plate. Extending downwardly from the front edge of the plate 58 is a sword 70 which, upon the plate being swung toward the horizontal by the action of magnet 68, enters an upwardly flared slot 71, Fig. 3, in the lower plate 43, thereby 25 accurately aligning the latter with the plate 58 and bringing the recess 60 into registry with the aperture 44. The spacing between the two plates in that position (indicated in dot-dash lines in Fig. 4) is such that the upper gripper 61, 62 will 30 be able to engage the cap 25 of a capsule 24 held between the jaws 47, 48 of the lower gripper.

A collector pipe 72, extending inclinedly below the platform 12, serves as an outlet for the loaded capsules and terminates in a funnel-shaped head 73 which penetrates the platform 12 below the position of plate 58 in substantial alignment with the recess 60 thereof. The pipe 72 may lead to any suitable depository (not shown) designed to receive the output of the apparatus.

In the third operating position of the arm 34 (Fig. 2) the aperture 44 of plate 43 is located below but eccentrically of the circular cutout 15 formed in the platform 11. This cutout serves for the insertion of a reservoir or cup 74 which contains the powder 75 to be loaded into the capsules 24, the cup being shown empty of powder in the cross section of Fig. 5. Cup 74 is provided along its upper edge with a lip 76 fitting into a corresponding recess around the cutout 15, this arrangement causing the cup to hang down into the housing 11-14 with its bottom positioned closely above the gripper 47, 48 of the plate 43. The cup 74 may be held in position by spring clips 77, mounted pivotably on the platform 11 for engagement with the lip 76, and may be closed by a cover 78 having a knob 79.

A vertical stud shaft 80 is journaled in the center of the cup bottom, this shaft having a frusto-pyramidal top 81 and carrying a pinion 82 at its lower end. The pinion 82 meshes with a gear 83 rotatably carried on the underside of the cup 74, this gear in turn being in engagement with a pinion 84 when the cup is in position within the cutout 15. Pinion 84 is carried on a vertical shaft 85 projecting from a box 86 which houses the motor 87 (see Fig. 7) as well as any required speed changer or other transmission means. By providing the pinions 82 and 84 with an equal number of teeth, shafts 80 and 85 will rotate in unison.

A wiper blade 88, of sector-shaped configuration, is removably positioned inside the cup 74 for rotation in the direction of the arrow (Fig. 5). This blade has a low trailing edge 89, a raised leading edge 90 and a hub 91 whose bottom re-

5

cess mates with the frusto-pyramidal top 81 of shaft 80, thereby coupling the wiper 88 to this shaft. Normally, i. e. in the quiescent condition of the apparatus, the wiper blade is in the position illustrated in dot-dash lines in Fig. 5 in which it overlies an aperture 92 provided in the bottom of the cup 74, this aperture having a diameter substantially equal to the inner diameter of capsule 24 and being aligned with the aperture 44 of plate 43 when the latter is in its position shown in Fig. 2.

The micro-switch 30 rests on a box 93 which contains a timer mechanism comprising a drum 94 and a motor 95 therefor, the latter being shown only in the circuit diagram of Fig. 7. Box 93 may also contain suitable transmission means coupling the motor 95 to the drum 94, as indicated schematically at 96 in Fig. 7, as well as a step-down transformer 97, rectifier 98 and smoothing network 99 whereby power is supplied to the motors 87, 95 from alternating-current mains 100.

Associated with drum 94 are ten wipers, designated 101 through 110, co-operating at various instants with corresponding contact strips provided on the face of the drum. Drum 94 is grounded, as is the positive terminal of the power source 98-100. A wiper 111 is connected in parallel with wiper 109 and co-operates with a grounded conductor strip 112 on a disk 113 with which it makes contact in all off-normal positions of the disk, the disk 113 being carried on the shaft 85 (indicated schematically in Fig. 7) to rotate in unison with wiper blade 88.

Negative bus conductor 114 is connected to wiper 101 via solenoid 32, to wiper 102 via magnet 49, and wipers 103, 104 and 105 via magnets 37, 38 and 39, respectively, to wiper 106 via solenoid 46, to wipers 107 and 108 via magnets 63 and 64, respectively, and to wipers 109, 110 via motors 87 and 95, respectively. The micro-switch 30 shunts the wiper 110 to ground.

The periphery of drum 94 is shown developed in Fig. 7 and on it are laid up a series of imaginary lines, designated 0 . . . 10, denoting successive time positions of the drum in respect to the wipers 101-110. These lines define ten intervals of equal duration which may each be equal to one second, for example, and which together form a complete cycle of operations of the timer and, therewith, of the entire apparatus. One such cycle will now be described.

With the mechanism at rest, the timer is in position 0 and the micro-switch 30 is open as shown. When power is connected to bus conductor 114, magnet 38 is energized via wiper 104 and causes the control arm 34 to assume its second, or intermediate, position so as to come into the field of attraction of magnet 37 if it had previously been in or near its third position adjacent the loading cup 74. When a magazine 23 full with capsules 24 is placed in the socket 17, micro-switch arm 29 is depressed and closes a circuit for the operation of motor 95. Drum 94 rotates and after a short time shunts the micro-switch 30 over a homing strip associated with wiper 110, thereby insuring continued operation of motor 95 until the mechanism returns to its starting position. At the same time the magnet 38 is de-energized and magnet 37 operates to swing the control arm 34 into its first position below the tube or chute 21.

In position 1 of the drum 94 the solenoid 32 operates momentarily and its plunger 33 ejects the lowest capsule 24 through the tube 21 as

6

indicated in dot-dash lines in Fig. 2. This capsule lands through the open jaws 47, 48 of the lower gripper (magnet 49 being unoperated) in the aperture 44 of plate 43. Switch arm 29 may rise for a brief instant during the movement of plunger 33, but this action has no effect in view of the shunt through wiper 110. Thereafter the magnet 49 attracts the movable jaw 47 is indicated in dot-dash lines in Fig. 3, the gripper thus closing about the capsule 24 and remaining in this position until the middle of the ninth interval.

At the end of the second interval the magnet 37 is de-energized and magnet 38 re-attracts the arm 34 to place plate 43 underneath plate 53 whose gripper 61, 62 is open at this time, magnet 64 being unoperated. Magnet 68 is energized in position 2½ of drum 94 to tilt the plate 53 downwardly, causing the upper gripper to embrace the cap 25 of the capsule 24 held in the lower gripper. At the beginning of the fourth interval magnet 64 is energized and causes gripper 61, 62 to close firmly about the cap 25. When magnet 68 releases shortly thereafter, spring 66 lifts up the plate 53 with its gripper, thereby removing the cap 25 from the capsule 24 is illustrated in Fig. 2. Magnet 38 now releases and magnet 35 swings the arm 34 into its third position below the cup 74.

When the now open capsule 24 has come to rest under the aperture 92 of cup 74, solenoid 46 operates in the fifth interval and causes the capsule as well as the gripper 47, 48 to rise, plunger 45 urging the capsule into firm contact with the underside of the cup 74 around the aperture 92. In the sixth interval the wiper 109 engages a conductive segment on the drum 94 to energize motor 86 which rotates shaft 85, disk 113, gears 82-84, shaft 81 and wiper blade 88. As soon as the disk 113 leaves its home position, wiper 109 is shunted over contact 111 and strip 112 so as to maintain the motor 86 operated after the wiper 109 has left its segment; the wiper blade 88 is thus carried through a complete revolution, motor 86 stopping when the disk 113 has returned to its starting position to break the connection between contact 111 and strip 112.

When the trailing edge 89 of the wiper clears the aperture 92, powder 75 begins to drop into the capsule 24 and fills it up; toward the end of its movement the raised leading edge 88 of the wiper blade sweeps over the aperture to clear it of excess powder, whereupon the blade comes to rest in its normal position which seals the bottom of the cup 74. If this bottom is thin enough, substantially all the powder remaining within the aperture 92 will adhere to the filling of capsule 24 when the latter descends in the middle of the seventh interval, as a result of the de-energization of solenoid 46, so that loading of the capsule can be accomplished practically without loss.

In position 7 of drum 94 the magnet 39 releases and magnet 38 restores the assembly 34, 43 to its second position aligned with the upper plate 53. Magnet 68 is thereafter re-operated to lower the plate 53, thereby replacing the cap 25 on the loaded capsule 24. In the middle of the ninth interval the magnets 49 and 68 release simultaneously and solenoid 46 is energized: Spring 66 now causes the gripper 61, 62 to lift up cap 25, together with the filled capsule 24 which has been released from the gripper 47, 48, the rise of plunger 45 insuring that the capsule is positively and instantaneously liberated from the jaws of the lower gripper. Solenoid 46 and magnet 38 are de-energized at the end of the ninth interval

and magnet 39 operates to swing the plate 43 out of the way; thereafter the magnet 64 releases and the jaws 61, 62 open, allowing the loaded capsule to drop into the collector 72, 73 at the bottom of the housing. The drum 34 returns to its starting position at the end of the tenth interval when the wiper 110 leaves its associated homing strip.

If the switch arm 29 is still depressed by the presence of one or more capsules in the magazine 23, the drum 34 will continue its rotation through an additional cycle or cycles. After, however, the last capsule has been ejected from the hopper, the arm 29 will rise within the recess 31 of the weight 28 so that the mechanism will come to rest after completing the revolution then in progress. The hopper 23 may then be refilled or replaced for the processing of additional capsules.

It will be apparent that the socket 17 will accommodate different magazines 23 of similar outer shape but varying internal dimensions to fit different sizes of capsules. Also, the grippers 47, 48 and 61, 62 are so designed as to be capable of engaging capsules and caps of varying length and diameter. Although a capsule will be loaded most efficiently if the aperture 32 of the powder reservoir 74 corresponds in diameter to the interior of the capsules, it will be apparent that a single cup 74 may be used for different sizes of capsules as long as the outer diameter of the capsule exceeds the diameter of that aperture. Cleaning of the cup 74 and the wiper blade 83, which are the only parts of the machine coming into contact with the powder 75, can be accomplished readily by removing the cup 74 from the cutout 15 and withdrawing the wiper blade 83 from the interior of the cup.

It is to be understood that the embodiment described hereinabove and shown in the drawing has been given merely by way of illustration and that its principal features may be embodied in apparatus of different structure without for this reason departing from the spirit of the invention or exceeding its scope as defined in the appended claims. Thus it may be mentioned that the discharge of the loaded capsule from the apparatus may proceed in a manner other than the one described, as by causing the upper gripper 61, 62 to open prior to the ascent of the plate 58, thereby leaving the capsule in its position on the lower plate 43, and operating the solenoid 46 after the release of the lower gripper 47, 48 to lift the capsule above the latter and allow it to drop over the edge of the plate 43 into the suitably positioned collector 72, 73; if desired, this last step may be accompanied by a tilting movement of the plate 43 brought about by the operation of some suitable, preferably electromagnetically controlled actuating member. The use of a blower to sweep the capsule off the plate 43 may be mentioned as a further possibility.

What is claimed is:

1. A device for the automatic filling of capsules with powder, comprising hopper means adapted to receive a series of empty capsules each having a body with a cap thereon; a horizontally movable first support; first control means for moving said first support between a first position adjacent said hopper means, an uncapping and recapping second position and a filling third position; a second support adjacent said second position movable in a vertical plane above said first support; filled-capsule discharge means below both said second position and said second

support; a powder magazine provided with an outlet above said third position; first gripper means on said first support; second control means for displacing said second support between an upper and a lower position; first actuating means synchronized with said first control means for closing said first gripper means around an empty capsule body in said first position and for maintaining said first gripper means closed during movement of said first support from said first position to said second and third positions and back to said second position, prior to opening of said first gripper means to release a filled capsule into said discharge means; second gripper means on said second support; second actuating means synchronized with said first and second control means for closing said second gripper means about said cap upon said first support occupying said second position for the first time and for opening said second gripper means upon the return of said first support with a filled capsule body to said second position, said second control means raising and lowering said second support in timed relationship with said second actuating means to uncap said capsule when empty and to recap said capsule when filled; and feed means at said powder reservoir for dispensing powder into the empty capsule body while in said third position.

2. A device according to claim 1, further comprising a swingable arm, said first support being mounted on said arm for horizontal swinging movement through said three positions thereof, said first control means comprising a plurality of magnets positioned along the path of said arm and electromagnetic circuit means for selectively energizing said magnets to attract said arm into respective ones of said three positions.

3. A device according to claim 1, further comprising a frame provided with a socket, said hopper means comprising a magazine removably fitting inside said socket.

4. A device according to claim 3 wherein said magazine and said socket are formed with aligned apertures, said ejector means comprising a plunger adapted to pass through certain of said apertures to force a capsule through other of said apertures.

5. A device according to claim 1, further comprising timer means synchronizing the operations of said first and second control means and first and second actuating means, a starting circuit for said timer means and switch means for closing said starting circuit, said switch means being provided with feeler means extending into said hopper means and causing the closing of said starting circuit in response to the presence of a capsule in said hopper means.

6. A device according to claim 5, further comprising homing means closing an alternative circuit for said timer means after the beginning of an operating cycle of the latter, thereby insuring completion of said cycle after ejection of the last capsule from said hopper means.

7. In a capsule filling device, in combination, a magazine adapted to receive a series of capsules, ejector means for discharging one capsule at a time from said magazine, support means movable to convey a discharged capsule toward a filling point, timer means controlling the operation of said ejector means and of said support means, a starting circuit for said timer means, and switch means for closing said starting circuit, said switch means being provided with feeler means extending into said magazine and

causing the closing of said starting circuit in response to the presence of a capsule in said magazine.

8. The combination according to claim 7, including a socket removably receiving said magazine, said socket and said magazine being provided with aligned openings, said feeler means comprising an arm extending through said aligned openings into contact with a capsule in said magazine.

9. The combination according to claim 8 wherein said magazine is an upright tube adapted to hold said capsules in vertically stacked position, said arm entering said tube from below and being depressible by the weight of a capsule 15 in contact therewith.

10. The combination according to claim 9,

including a weight member in said tube bearing upon said capsules, said weight member being provided at its underside with a recess adapted to receive said arm upon ejection of the last capsule from said tube, thereby removing pressure from said arm.

GERALD B. LAWRENCE.
